UNITED STATES PATENT OFFICE.

JOSEPH SALIM JOSEPH, OF GREENWOOD, MISSISSIPPI.

PUZZLE.

Application filed June 4, 1927. Serial No. 196,508.

This invention relates to geometrical puzzles consisting of a plurality of blocks or slices, such blocks being regular polygons, the main object of which is to construct a 5 large number of regular geometrical, and other figures, employing a comparatively small number of polygons by properly arranging and laying the polygons side by side edgewise.

10 Another object of the invention is to provide nine polygons out of which a large number of regular polygons and other figures may be selectively constructed by arranging said polygons laying them edge-
15 wise.

A further object of the invention is the provision of an article of manufacture consisting of a plurality of polygonal blocks which, when properly arranged as indicated 20 in a chart or diagram will selectively form a plurality of blocks of definite configuration.

In the drawings:

Figure 1 is a plan view showing the different elements assembled in a rectangular 25 figure,

Figure 2 is a plan view of one figure comprising all the pieces laid edgewise to form the same,

Figure 3 is a plan view showing by light 30 lines the juxtaposition of the elements that make Figure 2,

Figure 4 is a plan view of another polygon that can be made from the puzzle,

Figure 5 is a view showing by light lines 35 proper arrangement of the component parts of the block,

Figure 6 is another polygon and

Figure 7 is a light line view showing arrangement of blocks forming same,

Figure 8 is a view of a development of the 40 puzzle and Figure 9 is the appropriate line key to same,

Figure 10 is a view showing a trapezoid figure,

Figure 11 is the light line key to same,

Figure 12 is a view of another figure that can be developed from the component parts of the puzzle and

Figure 13 is its corresponding key,

Figure 14 is still another figure arising 50 under this puzzle and

Figure 15 is the light line key thereto.

Figure 16 is a view showing blocks arranged to provide an enclosed open figure,

55 Figure 17 is a sectional view showing another open figure.

It may be well to state at the outset that many different figures may be evolved from the nine blocks or pieces composing the puzzle. In fact three hundred and fifty have 60 already been developed and it is believed that it is capable of infinitely more than that number depending on the ingenuity and imagination of the operator.

The solution or secret of the game lies in 65 placing in proper juxtaposition edgewise each and every figure of the nine to form the various figures such as rectangle, perfect square, triangle, rhombus, trapezoid, etc.

As herein shown in Figure 1 the figure is 70 a rectangle comprising nine separate blocks, cards, or pieces which may be made of stone, composition, cardboard or the like, but they may be of any suitable material, light or heavy.

75 Triangles and trapezoids are used, there being seven of the former and two of the latter, the triangles being of various sizes and character while the trapezoids are alike in size and symmetrically arranged with 80 respect to the figure finally evolved.

All of the geometrical and other figures shown, and many others are formed by the same nine polygons or polygonal blocks or pieces, and comprising four isosceles triangles 3, 5, 6, and 8, three scalene triangles 1, 2 and 9 and two trapezoids 4 and 7. The triangles 5 and 6 are of like dimensions, and 3 and 8 are of like dimensions; the triangles 1, 2 and 9 are of unlike dimensions, 85 and the trapezoids 4 and 7 are of like dimensions.

When the polygons are disarranged they will present to the ordinary person a rather difficult problem or puzzle to arrange them 90 into the various figures shown in the drawing and on a chart or keybook that may be furnished with the blocks and forming a part of the puzzle, said chart or book being put up in the box containing the puzzle 95 blocks, and will provide a useful and educational amusement for children as well as adults. The chart may be printed upon cardboard or if desired on the cover of the box.

100 For the purposes of sale the polygonal blocks may be arranged into any one of the figures illustrated in the drawing and marketed in a suitable box. The faces of the blocks may bear designs or figures of any 105 fanciful or attractive type or advertisements may be printed thereon. As is shown in

Figures 16 and 17 the polygons may be so arranged as to leave various shaped open spaces.

While there is herein described and shown 5 the preferred embodiment of the present invention, it is nevertheless understood that minor changes may be made therein without departing from the spirit and scope of the invention as claimed.

10 What I claim as new is:

1. A nine figure puzzle comprising four isosceles triangles, three scalene triangles and two trapezoids, which when placed edge- 15 wise, form a plurality of figures including a rectangle and a star the isosceles triangles including a pair of similar dimensions and another pair of similar dimensions, but of

dissimilar dimensions from the first named pair.

2. A nine figure puzzle comprising four 20 isosceles triangles, three scalene triangles, and two trapezoids, which when placed together edgewise will form a plurality of figures, including a rectangle and a trapezoid, the trapezoid being symmetrically disposed with respect to the completed figure. 25

3. A nine figure puzzle comprising four isosceles triangles, three scalene triangles and two trapezoids, which when placed together edgewise will form a plurality of 30 figures, including a rectangle and an arrow head.

JOSEPH SALIM JOSEPH.
